SOCK

Paul E. Johnson, Jr., and Frank C. Owenby, Marietta, Ga.

Application July 15, 1957, Serial No. 46,933

Term of patent 14 years

(Cl. D47—7)

The figure is a rear elevational view of a sock, with the heel portion turned back, showing our new design.

The front of the sock is substantially the same in appearance as the portion disclosed excepting the buckle and strap effect on the cuff.

The characteristic feature of our design resides in the single strap member both ends of which are attached upon the rear of the cuff, said strap member having a buckle mounted thereon, as shown.

We claim:

The ornamental design for a sock, as shown and described.
